We claim the ornamental design for a CPR manikin, as shown and described.

DESCRIPTION

FIG. 1 is a top plan view of a CPR manikin showing our new design;

FIG. 2 is a top end elevational view thereof;

FIG. 3 is a bottom end elevational view thereof;

FIG. 4 is a right side elevational view thereof, the left side

elevational view being a mirror image thereof;

FIG. 5 is a rear plan view thereof; and,

FIG. 6 is a perspective view thereof.
